GASOLINE DISPENSER

Coates F. Bateman, Salisbury, Md., assignor to Symington Wayne Corporation, Salisbury, Md., a corporation of Maryland

Filed Feb. 12, 1960, Ser. No. 59,379

Term of patent 14 years

(Cl. D52—2)

Fig. 1.

FIG. 1 is a perspective view of a gasoline dispenser showing my new design; and

FIG. 2 is a perspective view of another embodiment of the gasoline dispenser.

The opposite side of the gasoline dispenser of FIG. 1 is substantially the same in appearance as the side shown and the end is the same as the end shown except that all of the accoutrements have been eliminated leaving the milled surface plate solid throughout.

The opposite side and end of the gasoline dispenser of FIG. 2 are substantially the same in appearance as the side and end shown.

The essential features of the design reside in the portions shown in full lines.

I claim:

The ornamental design for a gasoline dispenser, as shown and described.
